UNITED STATES PATENT OFFICE.

BENJAMIN F. NICHOLS, OF BROOKLINE, ASSIGNOR OF ONE-HALF TO JULIAN POMEROY, OF SPRINGFIELD, MASSACHUSETTS.

COUPLING.

SPECIFICATION forming part of Letters Patent No. 339,204, dated April 6, 1886.

Application filed December 9, 1885. Serial No. 185,150. (No model.)

To all whom it may concern:

Be it known that I, BENJAMIN F. NICHOLS, a citizen of the United States, residing at Brookline, in the county of Norfolk and State 5 of Massachusetts, have invented certain new and useful Improvements in Couplings; and I do hereby declare the following to be a full, clear, and exact description of the invention, such as will enable others skilled in the art 10 to which it appertains to make and use the same, reference being had to the accompanying drawings, and to letters or figures of reference marked thereon, which form a part of this specification.

15 This invention relates to "couplings" for uniting a series of lengths or joints longitudinally disposed end to end. Such component parts, when connected or made up, form one integral piece, as in the case of fishing-rods or 20 other similar articles.

The object of my invention is to form a coupling which shall be provided with means for automatically increasing their friction when made up—that is, the parts are so disposed that 25 they shall resist any tendency to partially disengage and separate, thereby rendering the adjacent lengths of the rod or other article loose and shaky, and nullifying the advantages which should be obtained were such component parts 30 connected firmly as a unit.

The drawings herewith shown represent, in Figure 1, a longitudinal central section of a self-locking coupling embodying my improvements. Figs. 2 and 3 are modifications.

35 In the above drawings, A B represent two adjacent lengths of a fishing-rod or other jointed article to be connected, while the coupling as an entirety is shown at C. This is composed, as usual, of male and female ferrule 40 parts, (respectively lettered a b.) The former is shown as a hollow ferrule inclosing the end of the length B, which is adapted to fit snugly and be secured within the same. Such ferrule is contracted at its closed end, which is provided with a central longitudinally-disposed screw-threaded stud, c.

The female part b of the coupling is represented as a hollow cylindrical ferrule open at both ends, one end of such ferrule being adapted to receive the extremity of the joint A, juxtaposed to B, to which it is to be united. The

other and opposite end of said ferrule is to receive the contracted portion of the male ferrule a, before described, which interlocks therewith.

55

To unite these ferrules a b, forming the coupling C as an entirety, and with it the contiguous lengths A B of the rod or other article, I have securely fastened an annular bushing, d, interiorly screw-threaded, within the bore of 60 the ferrule b. The screw-threaded stud c, before mentioned, is adapted to engage with and enter such bushing, and thus the parts of the coupling are interlocked and united.

I am aware that couplings very similarly 65 constructed in general principles have been used; but hitherto no means have been provided to automatically increase the friction of such devices—that is, after being once made up, there shall be no tendency to become loose 70 by the screw-threaded parts partially disengaging, which is a very objectionable feature in this class of fastenings, and I have herein endeavored to obviate this trouble, and at the same time improve the construction of the 75 coupling by the following arrangement of parts: It will be seen that the stud c is somewhat longer than the annular bushing d, through which it passes in screw-threaded engagement. Thus, when the shoulder on the closed end of 80 the ferrule a is in contact with the bushing, said stud projects beyond and bears against a metallic plate, e, loosely fitting and contained within the bore of the ferrule b. Now, between the butt-end of the joint A is disposed 85 a disk, f, of rubber or some other suitable elastic material, as a spring-washer; hence in the making up of the various lengths which compose a jointed fishing-rod or other similarly-constructed article, a female ferrule, b, is firmly 90 fastened to the lower end of each joint—in the present instance A. Furthermore, a male ferrule, a, is attached to the upper end of a length, B, and the two ferrules are then connected. The stud c, passing through and beyond the 95 end of the bushing d, bears against the metallic plate e and compresses the elastic medium f. The elasticity of the latter in striving to resume its normal shape exerts a continued forcible pressure against the plate and stud, 100 and thus serves most effectually the purpose of a check-nut, which cannot be used here,

owing to the peculiar disposition of the connecting parts.

It is evident that the thickness of the elastic medium may be increased, and consequently 5 the pressure, while the tendency of the stud to turn and so loosen the coupling is diminished.

In Fig. 2 is shown a modification of the elastic medium, which is represented by a spring-plate, in lieu of the elastic medium shown in 10 Fig. 1.

Fig. 3 shows a further modification, in which the bushing *d* is closed at one end, while an elastic medium is inserted in the bore thereof. Thus the stud, when turned home, shall bear 15 against and compress said medium, and an equivalent result is obtained.

I am aware that a coupling consisting of a male ferrule provided with a screw-threaded stud and secured to a female ferrule by means 20 of an annular screw-threaded bushing is not new. I am also aware that it is not new to lock the sections of a rod or other article together by means of set-screws which pass through an outside ring and then through the 25 ferrule and take into a notched cylindrical or smooth conical extension on the end of a male

ferrule, and I therefore do not claim such construction; but

I claim—

1. A coupling composed of male and female 30 parts, with the engaging screw-stud of the male adapted to compress an elastic medium contained within the female part of such coupling when the latter is made up, and for purposes stated.

2. The combination, with the ferrule *a* and screw-threaded stud *c*, of the ferrule *b*, screw-threaded bushing *d*, bearing-plate *e*, and elastic medium *f*, by means of which pressure is maintained against the stud to prevent unlocking of the parts, substantially as described. 40

3. In combination with two contiguous end-to-end lengths, *A* *B*, the coupling *C*, composed of the parts *a* *b* and their interlocking devices *c* *d* *e* *f*, all co-operating substantially for the 45 purposes herein set forth.

In testimony whereof I affix my signature in presence of two witnesses.

BENJAMIN F. NICHOLS.
